CLAIM

The ornamental design for a protective over cap for a for medicament stick holder, as shown and described.

DESCRIPTION

FIG. 1 is a perspective view of a protective overcap for a stick holder for medicament showing our new design;
FIG. 2 is a front elevational view thereof, the rear elevational view and the top and bottom plan views being the same;

FIG. 3 is a left end elevatioanl view thereof;

FIG. 4 is a right end elevational view thereof;

FIG. 5 is a longitudinal sectional view as taken generally along line 5—5 of FIG. 2; and,

FIG. 6 is an enlarged fragmentary sectional view taken generally along line 6—6 of FIG. 4.
